UNITED STATES PATENT OFFICE.

WILLARD F. RICHARDS, OF LANCASTER, NEW YORK, ASSIGNOR TO GOULD COUPLING COMPANY, OF NEW YORK, N. Y.

CAR-COUPLING.

1,105,839.

Specification of Letters Patent.

Patented Aug. 4, 1914.

Application filed July 7, 1910. Serial No. 570,757.

To all whom it may concern:

Be it known that I, WILLARD F. RICHARDS, a citizen of the United States, residing at Lancaster, in the county of Erie and State of New York, have invented a new and useful Improvement in Car-Couplers, of which the following is a specification.

This invention relates more particularly to car couplers of the Master Car Builders' type in which a vertically movable gravity-actuated lock for the horizontally-swinging knuckle and a horizontal lock lifting shaft, arranged transversely at the lower portion of the coupler head are employed.

The objects of the invention are to produce a strong and serviceable coupler of this type which will be easy to operate and positive and reliable in its automatic action, and which will be simple and inexpensive to manufacture and will not readily get out of order; also to provide a large and strong gravity-actuated knuckle lock which is actuated by a transverse rock shaft arranged at the bottom of the coupler head, and to arrange and connect the parts so that the lock cannot be jolted out of its locking position by the impact between two couplers in coupling the cars, and to improve the construction of couplers of this type in the respects hereinafter described and set forth in the claim.

In the accompanying drawings, consisting of three sheets: Figure 1 is a longitudinal sectional elevation of a car coupler embodying the invention, on line 1—1, Fig. 2, showing the locked position of the parts. Fig. 2 is a sectional plan thereof on line 2—2, Fig. 1. Fig. 3 is a sectional elevation similar to Fig. 1, showing the knuckle swung open. Fig. 4 is a sectional plan on line 4—4, Fig. 3. Fig. 5 is a transverse sectional elevation through the coupler, showing the lock in its set or released position. Fig. 6 is a similar view showing the knuckle locked.

Like reference characters refer to like parts in the several figures.

A represents the head, and B the horizontally-swinging knuckle of the coupler. The knuckle, as usual, is pivoted in the coupler head at one side thereof and is provided with an inwardly extending tail b and a lateral tail extension b' which is substantially concentric with the knuckle pivot and projects through a hole b² in the side

of the coupler head when the knuckle is closed. The tail of the knuckle has a flat side or face b³ adapted to be engaged by the knuckle lock for holding the knuckle in the closed or locked position.

The knuckle lock C is preferably arranged near the center of the coupler to move vertically between the face b³ of the knuckle tail and one of the upright side walls c of the coupler head. The lock extends up into a vertical guide cavity or pocket c' in the top of the head and is provided with a transverse upright slot c², and a horizontal pin c³, which is secured in any suitable manner in the coupler head and passes through the slot c² in the lock. The lower portion of the knuckle lock C is reduced in size, forming a leg or shank c⁴ which extends downwardly from the body of the lock through a slot c⁵ in the bottom of the coupler head A. The lock is thus adapted to move vertically in the head into and out of locking engagement with the tail of the knuckle and is guided in its vertical movements, and is held from movement laterally or sideways of the coupler by the pressure of the tail of the knuckle, due to the draft on the knuckle, thereby forming a very strong and reliable knuckle lock. The lower end of the shank of the lock is pivoted to an arm d on a horizontal operating rock shaft or rod D, which extends transversely underneath the coupler head and is journaled in suitable brackets or bearings d' depending from the bottom of the coupler head or in any other suitable manner. The rock shaft D is provided at one end with an eye d² or other suitable means by which an operating rod or lever (not shown) may be connected to the shaft D. When the operating shaft is rocked upwardly and rearwardly the lock is lifted vertically and its lower end is swung rearwardly owing to the pivotal connection of the shank of the lock with the rock arm d and the pivotal and sliding connection of its upper end with the pin c³, the lock being thus moved to a position such that the tail of the knuckle can swing outwardly under the large or body part of the lock.

E represents a lock set or latch which is pivoted at one end in any suitable way in a slot or recess e in the lock C so that its free end is adapted to swing toward the side of the coupler in which the knuckle is pivoted.

When the lock is in its lowest or locking position the side e' of the lock set will lie on the upper face of the knuckle tail, see Fig. 6. On raising the lock to release the knuckle, 5 the lock set will swing downwardly, its free end dragging along the upper face of the knuckle tail, until the lock set is arrested in a substantially upright position by the engagement of its face e' with the inner edge 10 of the slot e . When in this position, which is shown in Fig. 5, the lower end of the lock set is adapted to bear against the upper edge of the side b^a of the knuckle tail and thus hold the lock in the raised unlocking 15 position, shown in Fig. 5, until the knuckle has been swung open. The lower end of the lock set is preferably curved or inclined from the horizontal so that the lock set and lock will be raised slightly by the knuckle 20 when the knuckle is swung open.

F represents a knuckle opening lever or kicker which is pivoted between its ends in the coupler head at one side of the lock C on a pin f secured to the bottom of the coupler head or in any other suitable way. One arm of the lever extends forwardly and has a part f^a which is reduced in thickness to permit it to move underneath the knuckle tail, and an upwardly extending end lug or 30 portion f^b which is adapted to engage with a recessed part f^c at the lower portion of the knuckle tail. The other arm f^d of the lever F is curved around the knuckle lock C and the end thereof is adapted to be engaged and 35 moved rearwardly by the lock when the lock is thrown to its uppermost position, which will cause the front end of the kicker lever to press against the knuckle tail and thus swing the knuckle open.

40 In the operation of the coupler, the shaft D is rocked to raise the knuckle lock out of engagement with the knuckle tail and the lock may be set in that position, as before explained, if the coupler is in engagement 45 with an opposing coupler. If it is desired to swing open the knuckle, the shaft is rocked so as to throw the lower end of the lock forcibly backward beyond the set position and forcibly strike the rear end of the 50 kicker lever, thereby positively swinging this lever and opening the knuckle. After the lock is lifted clear of the knuckle tail, the

continued movement of the operating shaft simply swings the lower end of the lock rearwardly and the kicker lever can therefore 55 be struck a strong blow and actuated with but little exertion. When the knuckle is swung inwardly by the coupling cars its tail extension will engage the lock set E and swing it upwardly out of its holding position, so as to leave the lock free to drop to locking position when the knuckle is closed. Before the knuckle reaches the closed position its tail will strike the front 60 end of the kicker lever and swing the lever 65 on its pivot so that its rear portion will strike against the shank of the knuckle lock and force it forwardly beyond its dead center, after which the lock will drop to its locking position by gravity. Thus the operation of the coupler is positive and reliable and does not require the use of springs. The lower end of the lock has to swing rearwardly and upwardly to release the knuckle, and as the arm d of the lock-lifting shaft 75 occupies a nearly horizontal position when the knuckle is locked, the lock cannot be jolted out of holding engagement with the knuckle by the impact due to the coupling 80 of two cars.

The coupler is of simple construction and inexpensive to manufacture, and the parts composing it are strong and durable and not liable to become broken by the shocks to which the coupler is subjected in use. 85

I claim as my invention:

In a coupler, the combination of a swinging knuckle, a knuckle lock mounted in the coupler head to slide vertically and swing forwardly and rearwardly and having an enlarged upper portion adapted to lock the knuckle and a reduced shank depending through a hole in the bottom of the coupler head, and a lock-operating rock-shaft journaled externally at the bottom of 90 the coupler head and having an arm pivoted to said lock shank for raising and swinging the lock, substantially as set forth.

Witness my hand, this 5th day of July, 1910.

WILLARD F. RICHARDS.
